UNITED STATES PATENT OFFICE.

CHARLES G. CURTIS, OF NEW YORK, N. Y., ASSIGNOR, BY MESNE ASSIGNMENTS, TO GENERAL ELECTRIC COMPANY, A CORPORATION OF NEW YORK.

ELASTIC-FLUID TURBINE.

No. 928,109.

Specification of Letters Patent.

Patented July 13, 1909.

Application filed November 1, 1907. Serial No. 400,232.

To all whom it may concern:

Be it known that I, CHARLES G. CURTIS, a citizen of the United States, and a resident of the borough of Manhattan, city, county, and State of New York, have invented an Improvement in Elastic-Fluid Turbines, of which the following is a specification.

The object I have in view is the production of an elastic fluid turbine which will have advantages in economy and cheapness over those heretofore suggested. These objects are attained by the mechanism illustrated in the accompanying drawings, in which—

15 Figure 1 is a longitudinal section of a portion of a turbine embodying my invention. Fig. 2 is a detailed longitudinal section showing the effect of wear between the stationary and moving parts. Fig. 3 is a cross section 20 of the entire machine taken on the line 3—3 of Fig. 1 looking in the direction of the arrow. Fig. 4 is a detailed longitudinal section of a modification; and Fig. 5 is a further modification.

25 In all of the views like parts are designated by the same reference characters.

My invention has particular application to horizontal steam turbines for marine use, but the invention may be utilized in turbines in which the turning axis is not horizontal and for purposes other than marine, and for the utilization of elastic fluids other than steam.

30 The invention is shown as applied to a turbine of the axial flow type, but it is not so limited as certain features of construction may be utilized in connection with a turbine of different type.

In carrying out my invention I provide a 35 drum 1, upon which are carried the rows of moving buckets 2. The drum is mounted upon the shaft 3, which rotates in supporting bearings (not shown). The drum is incased within a shell 4, having ends 5, one being shown. The drum is of sufficient size to define, together with the shell, an annular space, a portion of which is the steam passage 40 through the turbine. This space is only enough deeper than the length of the buckets 45 and the depth of their bases and covers to provide a space in which the buckets will lie, giving large clearance so that there will be no danger of the fixed buckets striking the drum and the moving buckets striking the

shell. The intermediate or fixed buckets 6 are secured to the shell and lie in proper position between the moving buckets 2. In the structure illustrated the buckets are made in the manner usual to the Curtis turbine with bases and covers; different design 55 of buckets would require a difference in the depth of the annular space. The clearance between the bucket cover and the relatively moving surface in juxtaposition thereto can be large, as there is no material pressure difference between the discharge end of the nozzle and the exhaust side of the bucket wheel in a stage. This large clearance eliminates the danger of contact between the moving and fixed parts and makes a cheap construction. The steam passage will be of less 60 radial depth than the annular space, the portion of the space not occupied by the steam passage being occupied by the bucket bases, covers and clearances. The nozzle 7 in the end 5 of the casing directs the elastic fluid against the first row of moving buckets; and the fluid is transmitted alternately from 65 moving to fixed buckets until it is discharged from the last row of buckets in the machine. 70 The steam passage is divided by suitable means into stages, between which there is a pressure difference. One embodiment of 75 such means is a diaphragm; a number of these diaphragms 8 are illustrated and they are shown as carried by the shell. Each has 80 a very large central opening which surrounds the drum and makes as close a joint as possible with the latter.

For the purpose of taking full advantage 85 of the invention the drum is not reduced in diameter adjacent to a diaphragm, but on the contrary, keeps its full size throughout its length, diminishing only to accommodate buckets of greater depth. The diaphragms are provided with nozzles 9 for effecting conversion of a portion of the pressure of the fluid in the preceding compartment into velocity and directing it against the buckets in the succeeding compartment. 90 The fluid in each stage is discharged by a nozzle (as 7 or 9) and a portion or all of its velocity is fractionally abstracted by the rows of moving buckets within the stage. The nozzles 7 and 9 may be annular; that is, extend 95 around the entire peripheral circumference of the machine, or they may extend only part way around, or they may be inter-

rupted at intervals and extend non-continuously around the periphery. The diaphragms 8, as shown, are only as deep, (i. e., the distance from the outer edges to the center opening), as the annular space is wide, and do not extend down to the shaft. The area of surface subjected to a difference of pressure is therefore made very small. The improved design wherein the drum passes 10 through an opening in the diaphragm without diminution in diameter at that place produces a structure in which the dead space is reduced to a minimum and rotation losses are correspondingly reduced. The amount 15 of material used is also less, and the machine work is easier and simpler. Furthermore, the joint between the drum and the diaphragm can be reached for inspection or repair much easier than any structures in 20 which the diaphragm opening is smaller.

For the purpose of preventing leakage between the diaphragm and drum at the point where the latter passes through the former, the opening in the diaphragm should be as 25 small as possible without having the parts come into actual contact. In order to permit this to be done without danger should the parts unintentionally come in contact, I prefer to make one or the other of the parts 30 with annular ribs or rings 10, which in the embodiment illustrated in Fig. 2 are formed upon the diaphragm, although this is not necessary as they may be otherwise formed. These ribs are shown as comparatively deep 35 and narrow. When the parts come in contact, as they may in use through many causes, such as unequal expansion of the drum and shell, the wear or settling of the bearings or other reasons, the faces of the annular ribs will come in contact with the other 40 relatively moving body. The edges of the ribs will be spun or forced over, as shown in Fig. 2, the spaces between the ribs being sufficiently large to accommodate any material 45 thus forced over the edges of the ribs. These ribs should be, therefore, narrow enough and deep enough to permit their shapes to change by wear without destroying their continuity. Were these rings not present the contact of 50 the drum and diaphragm would result in a sawing or grinding action resulting in the tearing away of the diaphragm or drum so that the necessary close joint between the diaphragm and drum would cease to exist, 55 and the leakage losses would become high and other objections might result. The annular ribs also serve an additional purpose of producing baffling grooves making a labyrinthine passageway at the joint between the 60 drum and diaphragm, so that leakage is also reduced at this point for this reason.

In the modification shown in Fig. 4, the annular ribs are carried by the drum and not by the diaphragm. In this modification the 65 ribs are shown as formed separate from the

drum so that they may be removed and others replaced if necessary.

Another embodiment of the means for dividing the fluid passage into stages of different pressures is shown in Fig. 5. In lieu 70 of the diaphragms 8 is a row of buckets 11, such buckets being carried by one of the relatively rotating elements of the turbine, and extending with small clearance to the other element. In the embodiment illustrated the row of buckets is carried by the shell, but it may equally well be carried by the drum. The surfaces in juxtaposition may be provided with annular ribs similar to those already described, or the bucket covers 80 may be flat as shown, and will lie as close to the other relatively rotating element as is convenient. The top and bottom walls of the bucket will diverge so that a pressure drop will be produced, or other means utilized for this purpose. The other fixed and moving buckets will lie with large clearances in relation to the drum and shell.

In accordance with the provisions of the patent statutes, I have described the principle of my invention, together with the apparatus which I now consider to represent the best embodiment thereof, but I desire to have it understood that the apparatus shown is merely illustrative and that the invention 95 can be carried out in other ways.

Having now described my invention, what I claim as new and desire to secure by Letters Patent, is:

1. A turbine having a shell and a drum, 190 there being a passage for working fluid between the shell and drum, rows of fixed and moving buckets within the passage, with large clearances between the relatively moving surfaces, and means dividing the passage 105 into stages of different pressures, such means having small clearances, there being one row at least of fixed and a plurality of rows of moving buckets within each stage.

2. A turbine having a shell and a drum, 110 there being a passage for working fluid between the shell and drum, rows of fixed and moving buckets within the passage, with large clearances between the relatively moving surfaces and a diaphragm dividing the 115 passage into stages of different pressures, there being one row at least of fixed and a plurality of rows of moving buckets in each stage, the said diaphragm having a central opening in which the drum rotates.

3. A turbine having a shell and a drum, 120 there being a passage for working fluid between the shell and drum, rows of fixed and moving buckets within the passage, with large clearances between the relatively moving surfaces, and a diaphragm dividing the 125 passage into stages of different pressures, there being one row at least of fixed and a plurality of rows of moving buckets in each stage, the said diaphragm having a central 130

opening in which the drum rotates, and means at the joint for preventing leakage of fluid.

4. A turbine having a shell and a drum, there being a passage for working fluid between the shell and drum, rows of fixed and moving buckets within the passage, and a diaphragm dividing the passage into stages of different pressures, the said diaphragm having a central opening in which the drum rotates, and means at the joint for preventing injury of the parts when contact occurs.

5. A turbine having a shell and a drum, there being a passage for working fluid between the shell and drum, rows of fixed and moving buckets within the passage, and a diaphragm dividing the passage into stages of different pressures, the said diaphragm having a central opening in which the drum rotates, means at the joint for preventing leakage of fluid, and means at the joint for preventing injury of the parts when contact occurs.

6. A turbine having a shell and a drum, there being a passage for working fluid between the shell and drum, rows of fixed and moving buckets within the passage, and a diaphragm dividing the passage into stages of different pressures, the said diaphragm having a central opening in which the drum rotates, the opposing surfaces at the joint being arranged to permit lateral displacement of material when contact between the parts occurs.

35 7. A turbine having a shell and a drum, there being a passage for working fluid between the shell and drum, rows of fixed and moving buckets within the passage, and a diaphragm dividing the passage into stages of different pressures, the said diaphragm

having a central opening in which the drum rotates, an opposing surface having annular ribs, of sufficient depth and mutual separation to permit spinning when the parts are brought into contact.

8. A turbine having a shell and a drum, there being a passage for working fluid between the shell and drum, rows of fixed and moving buckets within the passage, and a diaphragm dividing the passage into stages of different pressures, the said diaphragm having a central opening in which the drum rotates, one of the opposing surfaces having annular ribs and the other being unribbed, the ribs being of sufficient depth and mutual separation to permit spinning when the parts are brought into contact.

9. A turbine having a shell and a drum, there being a passage for working fluid between the shell and drum, rows of fixed and moving buckets within the passage, and a diaphragm dividing the passage into stages of different pressures, the said diaphragm having a central opening in which the drum rotates, the surface of the diaphragm having annular ribs of sufficient depth and mutual separation to permit spinning when brought into contact with the drum, and the opposing face of the drum being unribbed.

10. A drum turbine divided into stages, with means for securing fractional abstraction, there being small clearances at points where pressure drop occurs, and large clearances within the stages.

This specification signed and witnessed 75
this 26th day of October, 1907.
